UNITED STATES PATENT OFFICE

2,613,838

REFRIGERATOR CABINET

Robert A. King, Erie, Pa., assignor to General
Electric Company, a corporation of New York

Application October 3, 1946, Serial No. 700,846

9 Claims. (Cl. 220—15)

1

My invention relates to refrigerator cabinets of the type including a metal inner liner secured in spaced relation to the outer cabinet shell and more particularly to arrangements for maintaining the required spacing between the shell and liner and for closing the space therebetween.

It is an object of my invention to provide a refrigerator cabinet having an outer wall and an inner wall in spaced relationship and including an improved arrangement for maintaining the sides of the outer wall and the inner wall in their required alignment.

It is another object of my invention to provide a refrigerator cabinet of the type having an inner metal wall spaced from an outer metal wall and an insulated breaker strip closing the space therebetween and including an improved arrangement for holding the breaker strip in its assembled position in a manner which allows easy assembly of the breaker strip and which prevents disengagement of the breaker strip after assembly.

Further objects and advantages of my invention will become apparent as the following description proceeds and the features of novelty which characterize my invention will be pointed out with particularity in the claims annexed to and forming a part of this specification.

For a better understanding of my invention reference may be had to the accompanying drawings in which Fig. 1 is a front elevation view, partly broken away, of a refrigerator cabinet incorporating my invention; Fig. 2 is an enlarged view showing details of the breaker strip assembly; Fig. 3 is a sectional view taken along the line 3—3 of Fig. 2; Fig. 4 shows a modified form of my invention; and Fig. 5 shows still another modification of my invention.

Referring to Fig. 1, I have shown a refrigerator cabinet 1 which includes a metal outer wall or shell 2 and a metal inner wall or liner 3. The cabinet is provided with a cover 4 for the machinery compartment and a door 5 for the food storage compartment 6. In order to maintain the outer wall and the inner wall in properly spaced relationship I provide a plurality of spacer assemblies indicated by 7 in this figure. The space between the outer wall and the inner wall is filled with a suitable heat-insulating material, and a breaker strip 8 is provided to close the opening between the outer wall and the inner wall along the area of the door frame.

In Figs. 2 and 3 I have shown details of one embodiment of my invention. A spacer 9, which

2

is composed of suitable heat-insulating material, is provided for maintaining the proper spacing between the free edge portions of the outer wall and the inner wall. The outer wall and the inner wall are secured against opposite ends of the spacer 9 by a bolt 10 and nut 11, or by any other suitable securing device. The bolt and nut are also employed to secure an element 12 adjacent the wall 2 inwardly of the free edge portion of the wall 2 and another element 13 adjacent the wall 3 inwardly of the free edge portion of the wall 3. Although I have shown the spacer mounted between inwardly extending portions of the walls, it will be apparent that individual brackets secured to the outer wall and the inner wall at suitable intervals could also be employed. In order to engage the edges of the breaker strip 8 and hold the latter in assembled position the element 12 is provided with a resilient flange 14 which presses against one edge of the breaker strip and the element 13 includes a resilient flange 15 which presses against the other edge of the breaker strip.

The end of the spacer is provided with a raised portion 16 of reduced size. A notch in the element 12 is arranged to engage this raised portion of the spacer to properly position the element 12 on the spacer. In order that the element 12 may be frictionally held in position it is made of greater thickness than the raised portion 16 of the spacer, and, when the assembly is made, the element 12 is therefore clamped in firm frictional engagement between the spacer 9 and the wall 2. The bolt 10 passes through an opening in the element 13 and, in its assembled position, presses the element 13 frictionally against the wall 3.

A portion 17 of the breaker strip 8 is made of arcuate cross section, and a portion of the spacer assembly is arranged to project into this curved portion of the breaker strip. In the embodiment shown in Fig. 2, the member or portion of the assembly so associated with the breaker strip consists of the head 18 of the bolt 10. When the breaker strip is assembled, one edge is placed under the resilient flange 14 of the element 12, and this flange 14 presses the breaker strip firmly against the side of the spacer 9. The other edge of the breaker strip is forced beneath the flange 15 of the element 13, and is pressed thereby toward the head 18 of the bolt 10. As can be clearly seen from Fig. 2, the head 18 of the bolt projects well into the concave portion 17 of the breaker

strip so that the breaker strip cannot move laterally a sufficient distance to become disengaged from beneath the flange 15. Thus the bolt 10 not only completes the spacer assembly and holds the wall 2 and the wall 3 in properly spaced relation, but it also prevents disengagement of the breaker strip during normal use of the refrigerator. Should it be necessary, however, to disassemble the breaker strip at any time, this can readily be accomplished by forcing the resilient flange 15 away from the edge of the breaker strip.

In Fig. 4 I have shown a modified form of my invention which includes a spacer 19 composed of suitable heat-insulating material. The spacer 19 is secured to the wall 2 by a washer 20 and a screw 21, which cooperates with a threaded bore in one end of the spacer, and it is secured to the wall 3 by a screw 22 which engages a similarly threaded bore in the other end of the spacer. In order to assist in supporting the breaker strip 8, the wall 2 is provided with a flanged portion 23. One edge of the breaker strip is pressed against the flanged portion 23 by a resilient flange 24 of an element 25. The element 25 is incorporated in the spacer assembly by the screw 21 which clamps the element 25 between the wall 2 and the spacer 19. A clamp 26 is arranged to engage the other edge of the breaker strip. This clamp 26 is held in assembled position on the wall 3 by a shelf support 27 and a cooperating screw 28, which engages the shelf support. As in the embodiment shown in Fig. 2, the breaker strip 8 includes a portion 17 which is of arcuate cross section. The concave face of this curved portion of the breaker strip is disposed toward a projecting portion of the spacer assembly which in the embodiment shown in Fig. 4 is represented by the head 29 of the screw 22. The rounded head 29 of the screw 22 projects into the concavity in the breaker strip a sufficient distance to limit the movement of the breaker strip to an amount which prevents disengagement of the edge of the breaker strip from beneath the clamp 26. Disengagement of the breaker strip is thus prevented in the same manner as previously described in connection with Fig. 2.

In Fig. 5 I have shown another embodiment of my invention which incorporates a modified form of spacer. The same numerals have been applied to corresponding parts in Figs. 4 and 5. The spacer indicated at 30 consists of a flat strip of heat-insulating material of rectangular cross section. The spacer is provided with notches 31 and 32 which engage the wall 2 and notches 33 and 34 which engage the wall 3. An element 35 is provided with a portion 36 which presses against one edge of the breaker strip to hold it in position against the outer shell and with a notched portion 37 which engages the spacer 30 to prevent turning movement thereof after assembly. The specific construction of the spacer shown in Fig. 5 and the details of its assembly between the outer wall and the inner wall are not my invention but are described and claimed in a copending application of Edwin H. Boddy Serial No. 700,901, filed October 3, 1946 and assigned to the same assignee as the present application. A rounded end 38 of the spacer 30 projects into the concavity formed by the curved portion 17 of the breaker strip 8. As can be seen by reference to Fig. 5 the end 38 of the spacer projects upwardly into this concavity a sufficient distance that movement of the breaker strip is

limited to an extent which will prevent the disengagement of the edge of the breaker strip from beneath the clamp 26.

In the modification shown in Fig. 5, the structural support of the inner wall on the outer wall is accomplished by elements other than the spacer assembly, as by corner pieces connecting the inner wall to the outer wall shown in the above-mentioned Boddy application. Similarly, in the constructions shown in the preceding figures, the spacer need not be the main structural element for supporting the inner wall on the outer wall, but such support can be accomplished by other members provided for that specific purpose such as the corner pieces shown in the aforementioned Boddy application.

From the foregoing it can be seen that I have provided a spacer assembly of simple construction which maintains the outer wall and the inner wall in the proper spaced relationship and which also maintains the breaker strip in its assembled position.

While I have illustrated and described my invention by reference to specific embodiments, I do not desire my invention to be limited to the particular constructions shown and described and I intend, by the appended claims, to cover all modifications which fall within the spirit and scope of my invention.

What I claim as new and desire to secure by Letters Patent of the United States is:

1. In a refrigerator cabinet, an outer wall and an inner wall mounted in spaced relationship, said walls terminating in spaced free edge portions, spacing means secured to said walls for maintaining the spaced alignment of said edge portions of said walls, a readily detachable breaker strip for closing the space between said walls and enclosing said free edge portions of said walls, resilient means secured to one of said walls inwardly of the edge portion thereof and engaging one edge of said breaker strip for retaining said breaker strip in position, said breaker strip being formed with a concave portion adjacent said one edge thereof and enclosing said one edge portion of said one of said walls, and means including a portion of said spacing means extending toward said concave portion of said breaker strip and arranged to engage said concave portion while said one edge of said breaker strip is in engagement with said resilient means to prevent disengagement of said breaker strip from said resilient means.

2. In a refrigerator cabinet, an outer wall, an inner wall arranged in spaced relationship to said first-named wall, said walls terminating in spaced free edge portions, a spacer secured to said walls for maintaining said edge portions in spaced alignment, a readily detachable breaker strip closing the space between said walls and enclosing said edge portions of said walls, said breaker strip being shaped to provide a concave portion adjacent one edge thereof and facing said spacer, means secured to one of said walls inwardly of the edge portion thereof and engaging said one edge of said breaker strip adjacent said concave portion, and means connected to said spacer and extending toward said concave portion of said breaker strip for engaging said concave portion while said breaker strip is in engagement with said first-mentioned means to prevent disengagement of said breaker strip from said first-mentioned means.

3. In a refrigerator cabinet, an outer wall, an

inner wall arranged in spaced relationship to said first-named wall, said walls terminating in spaced free edge portions, a readily detachable breaker strip closing the space between said walls and enclosing said edge portions of said walls, said breaker strip being formed to provide a concave portion adjacent one edge thereof and enclosing the edge portion of one of said walls, means secured to said one of said walls inwardly of said edge portion thereof and engaging said one edge of said breaker strip, and spacing means secured to said walls for maintaining said edge portions of said walls in spaced alignment, said concave portion of said breaker strip facing said spacing means, a portion of said spacing means projecting through said one of said walls and into said concave portion of said breaker strip and arranged to engage said concave portion while said one edge of said breaker strip is in engagement with said first-mentioned means to prevent disengagement of said breaker strip from said first-mentioned means.

4. In a refrigerator cabinet, an outer shell, an inner liner arranged in spaced relation to said outer shell, said outer shell and said inner liner terminating in spaced free edge portions, a spacer assembly for maintaining said edge portions of said outer shell and said inner liner in spaced alignment, a readily detachable breaker strip closing the space between said outer shell and said inner liner and overlapping said edge portions thereof, said breaker strip being shaped to provide a concave portion adjacent one edge thereof facing said spacer assembly and enclosing the edge portion of said inner liner, and means secured to said inner liner inwardly of said edge portion thereof and engaging said one edge of said breaker strip adjacent said concave portion, said spacer assembly including means extending toward said concave portion of said breaker strip for engaging said concave portion while said breaker strip is in engagement with said first-mentioned means to prevent disengagement of said breaker strip from said first-mentioned means.

5. In a refrigerator cabinet, an outer shell, an inner liner spaced from said outer shell, said outer shell and said inner liner terminating in spaced free edge portions, a spacer for maintaining said edge portions of said outer shell and said inner liner in spaced alignment, means securing said spacer between said outer shell and said inner liner, said means including a member projecting from said spacer through said inner liner, a breaker strip closing the space between said outer shell and said inner liner and enclosing said edge portion of said inner liner, and means secured to said inner liner inwardly of said edge portion thereof and engaging one edge of said breaker strip, said breaker strip being formed with a concave portion adjacent said one edge thereof and enclosing said edge portion of said inner liner and said member, said projecting member extending toward said concave portion of said breaker strip and being arranged to engage said concave portion while said breaker strip is in engagement with said last-mentioned means to prevent disengagement of said breaker strip from said last-mentioned means.

6. In a refrigerator cabinet, an outer wall, an inner wall arranged in spaced relation to said first-named wall, said walls terminating in spaced free edge portions, a spacer for maintaining said edge portions of said walls in spaced alignment, means securing said spacer to said walls, a breaker

strip closing the space between said walls and enclosing said edge portions of said walls, said breaker strip having a concave portion adjacent one edge thereof facing said securing means and enclosing the edge portion of one of said walls, and resilient means secured to said one of said walls and engaging said one edge of said breaker strip for pressing said breaker strip toward said first-mentioned means, said first-mentioned means extending toward said concave portion of said breaker strip for engaging said concave portion while said one edge of said breaker strip is in engagement with said resilient means to prevent disengagement of said breaker strip from said resilient means.

7. In a refrigerator cabinet, an outer shell, an inner liner arranged in spaced relation to said outer shell, said outer shell and said inner liner terminating in spaced free edge portions, a spacer for maintaining said edge portions of said outer shell and said inner liner in spaced alignment, resilient means secured to said outer shell, resilient means secured to said inner liner, means securing both the said resilient means and said spacer in position, a breaker strip closing the space between said outer shell and said inner liner and enclosing said edge portions of said outer shell and said inner liner, one edge of said breaker strip being engaged by one of said resilient means and the other edge of said breaker strip being engaged by the other of said resilient means, said breaker strip being shaped to provide a concave portion adjacent said one edge of said breaker strip and facing said securing means, said securing means extending toward said concave portion of said breaker strip for engaging said concave portion while said one edge of said breaker strip is in engagement with said one of said resilient means to prevent disengagement of said breaker strip from said one of said resilient means.

8. In a refrigerator cabinet, an outer wall, an inner wall arranged in spaced relation to said first-named wall, said walls terminating in spaced free edge portions, a spacer assembly maintaining said edge portions of said walls in spaced alignment, and a breaker strip closing the space between said walls and enclosing said edge portions of said walls, said breaker strip being shaped to provide a concave portion adjacent one edge thereof facing said spacer assembly, resilient means engaging said one edge of said breaker strip, said spacer assembly including means securing said resilient means in assembled position, said spacer assembly extending toward said concave portion of said breaker strip for engaging said concave portion while said one edge of said breaker strip is in engagement with said resilient means to prevent disengagement of said breaker strip from said resilient means.

9. In a refrigerator cabinet, an outer shell, an inner liner arranged in spaced relation to said outer shell, said outer shell and said inner liner terminating in spaced free edge portions, a spacer assembly for maintaining said edge portions of said outer shell and said inner liner in spaced alignment, and a breaker strip closing the space between said outer shell and said inner liner and enclosing said edge portions of said outer shell and said inner liner, said breaker strip being shaped to provide a concave portion adjacent one edge thereof facing said spacer assembly, a first resilient means pressing said one edge of said breaker strip against said inner liner, a second resilient means pressing the other edge

of said breaker strip against said outer shell, said spacer assembly including means for securing said two resilient means in position, said spacer assembly further including means extending toward said concave portion of said breaker strip for engaging said concave portion while said adjacent edge of said breaker strip is in engagement with said one edge of said breaker strip to prevent disengagement of said breaker strip from said first resilient means.
